UNITED STATES PATENT OFFICE.

EBEN PIERCE, OF NEW BEDFORD, MASSACHUSETTS.

BOMB-LANCE.

SPECIFICATION forming part of Letters Patent No. 320,393, dated June 16, 1885.

Application filed March 24, 1885. (No model.)

To all whom it may concern:

Be it known that I, EBEN PIERCE, a citizen of the United States, residing at New Bedford, in the county of Bristol, State of Massachusetts, have invented new and useful Improvements in Bomb-Lances, of which the following is a specification.

This invention relates to that class of bomb-lances for destroying whales and other animals, exemplified by my Patent No. 211,778, dated January 28, 1877, and in which an explosive charge contained in a proper magazine is fired by a fulminate-cap exploded by a hammer or plunger brought into action by the concussion caused by the discharge of the gun used for throwing the bomb-lance.

The object of my invention is to provide simple and effective means for insuring a regular ignition and burning of the fuse which fires the explosive charge, for preventing a premature explosion of the bomb-lance, or its explosion before the time predetermined upon.

Another object of the invention is to cause the fulminate-cap to ignite the fuse with certainty and precision by providing means for escape of the gases generated by the firing of the fulminate, and also preventing all liability of the cap nipple or tube from being battered out of shape by the hammer, which is liable to occur in bomb-lances heretofore devised, by reason of the direct connection of the cap-nipple with the fuse-tube and the mere provision of a very small orifice for the escape of the gases produced by the explosion of the fulminate.

In the present invention the cap or fulminate-nipple has no connection with the fuse-tube, and the fuse itself terminates in a space formed in the plug which carries the cap-nipple, the latter being supported in such a manner that a firm bearing is formed for preventing it from being battered by the plunger or hammer, thus removing all liability of the gas-escape orifice closing and preventing the fuse from being unevenly or irregularly ignited, or not ignited at all, by reason of the complete closing of the gas-escape and vent orifices.

In the accompanying drawings, Figure 1 is an elevation of a bomb-lance of the type in which my invention is embodied. Fig. 2 is a sectional view representing my improved fuse supporting and firing devices. Fig. 3 shows

detailed sectional views of the screw-plug, fuse tube, and independent fulminate-cap tube. Fig. 4 is a detail view of the hammer or plunger for exploding the cap.

The reference numeral 1 designates the barrel or magazine of a bomb-lance, which contains a charge of powder or other explosive material. The magazine-chamber is closed at one end by means of a cylindrical plug, 2, which has a continuous screw-thread engaging with an interior screw-thread in the magazine and with a similar screw-thread of a hollow extension, 3, of the lance or harpoon-head 4. The rear end of the magazine is closed by means of a screw-plug, 5, which is extended to form a hollow stem, 6, to give the lance the requisite length. The stem 7 has a disk, 8, at its rear end, for properly packing the lance in the gun-barrel, and said stem is also provided with wings or feathers 9, for insuring an accurate flight of the lance. The plug 2 has an aperture, 10, extending axially through the same, and its front end is provided with slots 11, which intersect or communicate with said axial bore, as is clearly shown in Fig. 3. A tube, 12, extending from the rear end of the plug 2, serves for the reception of a fuse, 13, which is of such a nature and is so disposed as to effect a firing of the charge in the magazine when said fuse has burned to its rear end. The tube 12 is screw-threaded at its front end, and enters a screw-threaded portion of the axial bore 10 to such an extent as will leave the remainder of said bore free for the reception of the fuse and the tube-extension 14 of the nipple 15. The latter has a flange, 16, at its base, which rests upon the front end of the head 2, a wire or other suitable device serving to hold the nipple and the cap placed thereon in position, as is indicated in Fig. 2. The tube-extension of the nipple enters the axial bore of the plug, and is made sufficiently smaller than said bore so as to leave an annular space which communicates with the slots 11. It is evident that by such arrangement a large vent-passage is formed, which is always open, and will effectually serve to convey the gases caused by the explosion of the cap from the bore of the plug outward into the point 4. The cap is exploded by means of a plunger or hammer, 17, which is held at the front of the hollow extension of

the lance-head by means of a break-pin, 18. When the lance is fired from a gun, the concussion will cause said pin to break, thus throwing the hammer upon the cap placed on 5 the nipple and igniting the fuse. It is evident that by reason of said fuse not being inclosed at its front end that an absolute and even ignition always takes place, and since the cap-nipple and its tube-extension form no part of 10 the fuse-tube, but are supported upon the plug 2 in the manner already stated, it will be seen that I obviate all danger or liability of the ignition and combustion of the fuse being irregular or out of time. For these reasons 15 the explosion of the charge in the magazine takes place at the time predetermined upon, according to the length or nature of the fuse. The latter is secured by means of a wrapping, 36, of twine, wire, or other suitable material, 20 which lies in a segmental slot, 20, inside near the inner end of the fuse-tube, a suitable coating of wax or other material being applied to the wrapping for tightening the same and causing the fire of the fuse to pass beyond the 25 fuse-tube in order to consume the projecting portion of the fuse.

I have shown the nipple as constructed to receive a gun-cap for igniting the fuse, but I intend to also use what is termed a primer for 30 this purpose, and where a primer is employed the nipple will be constructed in a manner suitable to receive it. The cap is held upon the nipple to prevent accidental displacement by means of a wire which passes over the head 35 of the cap and has its ends secured to the front closing plug.

What I claim is—

1. The combination, with the magazine of a bomb-lance, of the front closing-plug having 40 an axial bore and provided in its outer end with lateral slots or openings intersecting said

bore, the independent nipple arranged in and of a less diameter than said bore and seated upon and supported by the outer end of the front closing-plug, and the fuse-tube extending from the rear end of said plug, substantially as described. 45

2. The combination, with the magazine of a bomb-lance, of the front closing-plug having an axial bore and provided in its outer end 50 with lateral slots or openings intersecting said bore, the nipple having a tube-extension and provided with a horizontal flange seated upon and supported by the outer end of the plug.

3. The combination, with the magazine of a bomb-lance, of a front closing-plug having an axial bore and slots intersecting the upper end thereof, an independent nipple having a tubular end extending within the bore of the plug and provided with an annular flange 60 that rests upon the end of the plug above its slots, and a wire for confining the cap on the nipple, substantially as described. 55

4. In a bomb-lance, the combination of the plug having an axial bore and openings communicating therewith, the independent nipple-tube supported upon the front end of said plug, and the fuse-tube extending from the rear end of said plug with the magazine, the lance-head, and the plunger or hammer, substantially as described. 65

5. In a bomb-lance, the combination of the nipple, the plug having the axial bore, and the fuse-tube with the wire for holding the cap on the nipple, substantially as and for the purpose described. 70 75

In testimony whereof I affix my signature in presence of two witnesses.

EBEN PIERCE.
